CLAIM

The ornamental design for a data loop transceiver for coupling data between computer peripherals, as shown and described.

DESCRIPTION

FIG. 1 is a perspective view of the data loop transceiver for coupling data between computer peripherals in accordance with my new design;

FIG. 2 is a top plan view thereof;

FIG. 3 is a front elevational view thereof;

FIG. 4 is a bottom plan view thereof;

FIG. 5 is a right side view thereof, the left side view

being identical thereto; and,

FIG. 6 is a rear elevational view thereof.

FIG. 1

FIG. 2

FIG. 3

FIG. 4

FIG. 6

FIG. 5
